UNITED STATES PATENT OFFICE.

JAMES McENTEE, OF ROCHESTER, NEW YORK, ASSIGNOR TO BASTIAN BROTHERS COMPANY, OF ROCHESTER, NEW YORK, A CORPORATION.

DESIGN FOR AN ADVERTISING DEVICE.

48,980.

Specification for Design.

Patented May 2, 1916.

Application filed February 11, 1916. Serial No. 77,813. Term of patent 3½ years.

To all whom it may concern:

Be it known that I, JAMES McENTEE, a citizen of the United States, residing at Rochester, in the county of Monroe and State of New York, have invented a new, original, and ornamental Design for an Advertising Device, of which the following is a specification, reference being had to the accompanying drawings, forming a part thereof.

In the drawings: Figure 1 is a front-elevation of a device showing the novel design hereinbefore referred to; and Fig. 2 is a perspective view of the same, both views being on an enlarged scale.

The design represents a novelty intended for use as an advertising device, which may be attached to the person or otherwise used.

It comprises a transparent portion *a* simulating a wind-shield of an automobile, and a portion *b* which may be opaque or translucent, and to which advertising-matter may be applied. A pin *c*, shown in dotted lines, is usually employed to support the device, but this pin does not constitute an essential part of the design.

I claim:—

The ornamental design for an advertising device as shown and described.

JAMES McENTEE.
